DESIGN FOR A REFLECTOR-SHADE

William Richard Krebs, Grantwood, N. J.

Application September 6, 1933. Serial No. 49,210

Term of patent 7 years

To all whom it may concern:

Be it known that I, WILLIAM RICHARD KREBS, a citizen of the United States, residing at Grantwood, in the county of Bergen and State of New Jersey, have invented a new, original, and ornamental Design for a Reflector-Shade, of which the following is a specification, reference being had to the accompanying drawing, forming part thereof.

I claim:

The ornamental design for a reflector-shade, as shown.

WILLIAM RICHARD KREBS.
